(57) **CLAIM**

The ornamental design for a pallet lifter, as shown and described.

DESCRIPTION

FIG. 1 shows a right side view of my design for a pallet lifter; FIG. 2 shows a front view thereof;

FIG. 3 shows a front perspective view thereof;

FIG. 4 shows a rear perspective view rotated 90 degrees thereof;

FIG. 5 shows a top plan view thereof;

FIG. 6 shows a left side view thereof; and,

FIG. 7 shows a rear view thereof.

The bottom view forms no part of the claimed design.
